C. A. BULL.

PIN TRAY.

APPLICATION FILED JULY 2, 1917.

1,258,531.

Patented Mar. 5, 1918.

FIG. 1.

UNITED STATES PATENT OFFICE.

CHARLES A. BULL, OF ALBION, NEBRASKA.

PIN-TRAY.

1,258,531.

Specification of Letters Patent.

Patented Mar. 5, 1918.

Application filed July 2, 1917. Serial No. 178,319.

To all whom it may concern:

Be it known that I, CHARLES A. BULL, a citizen of the United States, residing at Albion, in the county of Boone and State of Nebraska, have invented certain new and useful Improvements in Pin-Trays; and I do declare the following to be a full, clear, and exact description of the invention such as will enable others skilled in the art to 10 which it appertains to make and use the same.

My invention relates to pin trays and has for its object to provide a pin tray in which a novel means is provided for holding a plurality of pins in the tray in such a manner as to be readily withdrawn therefrom.

A further object of the invention is to so construct a tray of this character that all parts will be readily accessible and disposed 20 most advantageously and which will be cheap to manufacture and most efficient.

With these and other general objects in view which will appear from the description, my invention resides in the novel features of construction, combination and arrangement of parts to be more fully described and claimed and taken in connection with the accompanying drawings which form a part of this application and in 30 which:

Figure 1 is a perspective view of my improved pin tray;

Figs. 2 and 3 are transverse sectional views on the lines 2—2 and 3—3 of Fig. 1, 35 respectively; and,

Fig. 4 is a longitudinal vertical sectional view on the line 4—4 of Fig. 1.

My improved attachment comprises a rectangular tray of glass, porcelain, metal or 40 any suitable material preferred having a base 1 which is provided with an upstanding relatively wide hollow wall 2 along one longitudinal side and both ends. The top of the wall which is designated as 3 is closed 45 and perforated at spaced intervals to form a series of alined apertures 4. The inner side of the upstanding wall is left open throughout its length and a strip of coarse felt or other cushion material 5 is adapted 50 to be inserted through the open side into the hollow interior of the wall to completely fill the same. As a means of retaining the cushion material firmly within the wall, I provide a pair of ribs 6 extending horizontally 55 throughout the length of the walls at opposite sides of the same and spaced

slightly above the bottom so as to firmly wedge the cushion material therebetween and hold the same firmly within the wall.

This construction provides a means whereby a plurality of pins may be inserted 60 through the apertures 4 and will be held embedded in the cushion material 5 in spaced relation so as to be readily removed therefrom.

Adjacent the open longitudinal side of the tray, the base is provided with a series of parallel longitudinally disposed grooves 7 for the reception of pens, pencils and the like therein and the base at this point along 70 the open longitudinal side is slightly raised as at 8. Between the two longitudinal side walls of the base, a suitable space will be provided for the reception of one or more ink wells 9 which may be rounded or 75 squared or of any suitable configuration to be retained on the base and which are provided with removable covers 10 having inwardly slanting guide spouts 11 through which the pen point is to be inserted to the 80 interior of the ink well.

Adjacent the ends of the tray, the base is provided with upright pins 12 anchored in the base and longitudinally with the pins, the base is provided with a pair of elongated 85 transversely disposed slots for the reception therethrough of removable pins 13 having burs 14 at their lower ends whereby the pins may be adjustably secured in the slots. This adjustment of the pins provides an extensible paper clip holder as the pins may be adjusted to receive any size of looped paper clips thereover and may be adjusted as desired.

While I have described and illustrated in 95 the accompanying drawings certain approved details and materials entering into the construction and operation of the invention, I desire it to be understood that I do not intend to limit myself specifically to 100 these but that any changes or alterations may be made in the same as will fall within the scope of the invention as claimed.

I claim:—

1. A device of the character described 105 comprising a pin tray, a hollow upstanding wall formed integral on the back and sides of the tray, said wall having an opening formed on its inner side, cushion material disposed in said wall through said opening, 110 means to retain said material therein, the top of said wall being perforated to receive

pins therethrough and maintain the pins in spaced relation in the cushion material.

2. A device of the character described comprising a pin tray, a hollow upstanding wall formed integral on the back and sides of the tray, said wall having an opening formed on its inner side for the insertion of a cushion material, ridges on the inner surfaces of said hollow wall to retain said cushion material therein and the top of said wall being perforated at spaced intervals to re-

ceive pins therethrough and maintain the same in upright spaced relation in said cushion material.

In testimony whereof I have hereunto set my hand in the presence of two subscribing witnesses.

CHARLES A. BULL.

Witnesses:

WARD MCKELLIPS,
D. G. HOWELL.
